(57) **CLAIM**

The ornamental design for a combination pen and notepad holder, as shown and described.

DESCRIPTION

FIG. 1 is a perspective view of the combination pen and notepad holder of the invention taken from the front and left in which the combination pen and notepad holder is in an attached configuration;

FIG. 2 is a perspective view of the combination pen and notepad holder of the invention in the configuration shown in FIG. 1 taken from the rear and left;

FIG. 3 is a right side view of the combination pen and notepad holder of the invention in the configuration shown in FIG. 1;

FIG. 4 is left side view of the combination pen and notepad holder of the invention in the configuration shown in FIG. 1; FIG. 5 is a front elevation view of the combination pen and notepad holder of the invention in the configuration shown in FIG. 1;

FIG. 6 is a rear elevation view of the combination pen and notepad holder of the invention in the configuration shown in FIG. 1;

FIG. 7 is a bottom end view of the combination pen and notepad holder of the invention in the configuration shown in FIG. 1;

FIG. 8 is a top end view of the combination pen and notepad holder of the invention in the configuration shown in FIG. 1;

FIG. 9 is a front perspective view of the combination pen and notepad holder of the invention in which the combination pen and notepad holder is in a detached configuration and the notepad holder is in an open position showing the disposition of a pad of paper therein;

FIG. 10 is a rear perspective view of the combination pen and notepad holder of the invention in the configuration shown in FIG. 9; and,

FIG. 11 is a perspective view of the combination pen and notepad holder of the invention taken from the front and left in which the combination pen and notepad holder is in an attached configuration and the notepad holder is in an open position showing the disposition of a pad of paper therein.
